UNITED STATES PATENT OFFICE.

WILLIAM E. DOUGHTY, OF DETROIT, MICHIGAN.

DESIGN FOR A DISPLAY CONTAINER.

Application filed July 5, 1927. Serial No. 22,667. Term of patent 14 years.

To all whom it may concern:

Be it known that I, WILLIAM E. DOUGHTY, a citizen of the United States, residing at Detroit, in the county of Wayne and State of Michigan, have invented a new, original, and ornamental Design for a Display Container, of which the following is a specification, reference being had to the accompanying drawing, forming part thereof.

I claim:

The ornamental design for a display container as shown.

WILLIAM E. DOUGHTY.
